ATTORNEY.

UNITED STATES PATENT OFFICE.

FRANK A. PERRET, OF BROOKLYN, NEW YORK, ASSIGNOR TO THE ELEKTRON MANUFACTURING COMPANY, OF SAME PLACE.

ELECTRIC CONTACT DEVICE.

SPECIFICATION forming part of Letters Patent No. 448,669, dated March 24, 1891.

Application filed June 28, 1890. Serial No. 357,088. (No model.)

To all whom it may concern:

Be it known that I, FRANK A. PERRET, a citizen of the United States, residing in Brooklyn, in the county of Kings and State of New York, have invented certain new and useful Improvements in Electric Contact Devices, of which the following is a specification.

This invention has reference to improvements in carbon-brushes or contact devices for conveying a current of electricity to and from a moving body, such as the commutator of a dynamo-electric machine and is designed to obviate the chief objections to carbon-brushes used heretofore, which are that however large the brush may be there is usually only one small part of it in actual contact with the commutator, and that consequently there is high resistance, heating, and sparking attending their use.

My invention insures a number of good contacts in each brush, and consequently reduces the resistance and removes all tendency to spark.

In general terms, the invention consists of a base or holder provided with chambers, in which are loosely placed pencils or blocks of carbon, in combination with springs arranged to act independently upon the respective carbon pencils to force them toward the surface against which it is to make a working contact. The pencils are easily removable from the block whenever it is desired to replace them for any purpose.

The invention will now be described with reference to the accompanying drawings, in which—

Figure 1 represents a perspective view of a block or holder with two rows of chambers; Fig. 2, a section of the same with screw-caps and carbons in place; Fig. 3, a perspective view of the block with a single row of chambers. Figs. 4 and 5 are views of modified forms. Fig. 6 is an end view of a commutator, showing the position of the contact device in relation thereto; and Fig. 7 is a view showing how a pair of the contact devices are set with respect to each other.

A represents the block or base, which may be made of metal or any conducting substance. This block is provided with two rows of holes a , the holes of each row being placed

opposite the spaces between the holes of the other row, and the diameter of the holes being a little greater than the spaces between the holes.

In the construction shown in Figs. 1 and 2 the upper ends of the holes are screw-threaded to receive screw-plugs a' . In each hole is placed a pencil of carbon of such diameter that it will easily slide therein. The pencils are all of the same size, and they project a short distance—say a half inch or less—below the lower side of the block. Between their inner ends and the screw-plugs are placed coil-springs a^2 , having a tendency to force the pencils out.

When the device is used as a collecting-brush for dynamo-electric machines, the block A is supported adjacent to the commutator B in such a manner that the pencils will stand in radial planes against the surface of the commutator. The block will of course be connected to an adjusting-yoke of any suitable description, and may be set as close to the commutator as desired. It will be observed that with this construction I am able to adjust the pressure of each pencil against the moving surface independently of the others, and with the greatest delicacy, this being accomplished by screwing the plugs a' in or out. Owing to the location and diameter of the carbon pencils, it will be observed that the whole surface of the commutator rotating immediately beneath the block will be covered by the pencils, so that the commutator will be worn evenly instead of in grooves, as would be the case if arranged otherwise. When brushes of the form shown in Fig. 3—that is, with one row of pencils—are used, the two brushes are set so that the pencils of one brush will occupy the planes between the pencils of the other brush, as shown in Fig. 7. This will also insure even wearing of the commutator. I find that the resistance of this brush is very low and that sparking is reduced to a minimum, each pencil being independently acted upon by its spring, constant and ample contacts are secured.

Fig. 4 shows the carbons extending beyond both ends of the block and with the springs connected at one end to the head of the pencil and at the other end to the block. In this

construction I use longer pencils and take advantage of the greater contact-surface in the block, besides which the carbons may be removed and replaced with greater facility.

5 In Fig. 5 the perforations in the block do not extend entirely through, but are in the form of chambers, a spring being first placed in each chamber and the pencils then put in.

10 My invention is not restricted to any particular form of chamber, hole or pencil, or to any particular number in each holder or any particular number of rows. The arrangement need not be in rows either, although I prefer it.

15 Having thus described my invention, I claim—

1. A contact device or brush consisting of a block or holder provided with two rows of perforations or chambers, the perforations or 20 chambers of each row located opposite the spaces between the perforations or chambers of the other row, the diameter of the perfora-

tions or chambers being greater than the spaces between the same.

2. A contact device or brush consisting of 25 a block or holder provided with a plurality of perforations or chambers, a carbon pencil in each perforation or chamber, a spring for each pencil, and a separate adjusting device for each spring for varying the tension.

3. The combination, with a commutator, of a pair of brushes, each consisting of a holder and a row of pencils, the brushes being set with the pencil of one brush standing opposite the spaces between the pencils of the 35 other brush, so that the wear on the commutator will be even instead of in grooves.

In witness whereof I have hereunto signed my name in the presence of two subscribing witnesses.

FRANK A. PERRET.
